UNITED STATES PATENT OFFICE.

EDWARD A. OWENS, OF SAN FRANCISCO, CALIFORNIA, ASSIGNOR TO SELECTASINE SYSTEM, INC., OF SAN FRANCISCO, CALIFORNIA, A CORPORATION OF CALIFORNIA.

METHOD OF PREPARING MASKING FILMS AND APPLYING THEM TO PRINTING STENCILS.

Application filed October 3, 1927. Serial No. 223,570.

This invention relates to a method of preparing masking films and applying them to printing stencils and it is an improvement over the methods described in the following 5 patents issued to Edward A. Owens et al., entitled "Method of delineating or reproducing pictures and designs," No. 1,254,764, issued January 29, 1918; Edward A. Owens "Method of making multi-color pictures," 10 issued February 17, 1925, No. 1,526,928; and Jacob H. Steinman, "Method of producing pictures in colors," No. 1,444,531, issued February 6, 1923.

The patents above referred to relate to 15 different methods whereby multi-colored pictures or designs may be produced by forcing colors, such as paints or the like, through a stencil screen, portions of which are temporarily masked out as the successive colors are applied. One patent describes a method whereby a multi-colored picture or design is produced by overlaying the colors, i. e., piling them one on top of the other. The second patent distinguishes 20 over the first to the extent that the colors employed will not overlay a preceding color, nor will embossed or raised effects be obtained. Conversely, the colors are laid side by side in adjoining areas. The third patent 25 is similar to the second with the exception that the color areas are outlined or defined by an intermediate key line. The method forming the subject matter of the present invention is applicable to any one of the 30 methods specified in the above patents.

The object of the present invention is to 35 generally improve and simplify methods of the character described; to provide a method whereby a picture or design containing one or more colors may be delineated or reproduced on a semi-smooth or rough surface, such as paper, card-board, linoleum, leather, fabrics, wood, glass, metal, etc., by forcing the colors through a printing stencil, portions 40 of which are temporarily or permanently masked out as the successive colors are applied; and more particularly, to provide a method of preparing masking films and applying them to the printing stencil. 45 The method is shown by way of illustration in the accompanying drawings in which:

Fig. 1 is a view of the original multi-colored sketch or design to be reproduced,

Fig. 2 is a perspective view of the master

stencil showing the outlining of the design 55 traced or otherwise reproduced thereon,

Fig. 3 is a perspective view of the master stencil showing it prepared for the production of the first masking film which is to be applied to the printing stencil, 60

Fig. 4 is a view showing the masking film applied to the transfer sheet,

Fig. 5 is a perspective view of the printing stencil showing it prepared for the first color run, 65

Fig. 6 is a view of the product obtained from the printing stencil after the first color has been run,

Fig. 7 is a perspective view of the master stencil showing it prepared to produce the 70 second masking film,

Fig. 8 is a view showing the second masking film applied to the transfer sheet,

Fig. 9 is a perspective view of the printing stencil showing the second masking film applied thereto, 75

Fig. 10 shows the completed product of the printing stencil after the second color run,

Fig. 11 is a perspective view of the printing stencil showing the method of positioning and applying the masking films to the 80 printing stencil.

The method forming the subject matter of the present application may for purposes of 85 description be considered as involving three main steps. First the preparation of the master stencil, secondly, the production of the masking films from the master stencil, and third, the application or transfer of the 90 masking films to the printing stencil.

For the purpose of rendering the description of the present method as simple as possible, the sketch or design to be reproduced is made as simple as possible and consists, as shown in Fig. 1, of a red circular disc, as indicated at A, enclosing a blue square B in the center of which is formed a white circular center C. The number of color runs required for a design of this 100 character will be two, to-wit, red and blue, as the color of the card or surface to which the design is applied happens to be white. The first step necessary is to provide a master stencil such as shown in Fig. 2. This 105 consists of a rectangular frame 2 over which is stretched or otherwise secured, a comparatively fine fabric, such as silk bolting cloth

or the like. This material is fairly transparent and the design to be reproduced is placed below the fabric and the outline of the design, to-wit, the two circles indicated at A and C, together with the square B is traced thereon with link or any other suitable material. Two markers are also traced on the silk as indicated at 3 and 4, these being provided for purposes of register and alignment as will hereinafter be described. After the outline of the design has been traced or otherwise applied to the surface of the master stencil, all of the surface thereof is blocked out with a permanent filler such as indicated at 5, i. e., the permanent filler completely closes the meshes of the material with the exception of that surface which comes within the circle A. This is temporarily left open as it is later on masked out 20 with a temporary blocking out material as shown in Fig. 3.

All the art work required in connection with the present method is performed on the master stencil, and outside of that the master 25 stencil only performs one function, to-wit, that of producing the masking films shown in Figs. 4 and 8 which are later transferred to the printing stencil, as shown in Figs. 5 and 9. With the master stencil prepared as 30 shown in Fig. 2, it is ready to receive the temporary blocking out material. This material is shown at 6 in Fig. 3. In other words, practically all that portion of the screen which was left open in Fig. 2 is temporarily blocked out with the material 35 shown at 6, with the exception of that small area indicated by the circle C, and when this blocking out material has set and dried, the master stencil is ready for the production of 40 the first masking film which in this instance is shown at 7 in Fig. 4.

Before proceeding further with the description, it might be advisable to specify certain materials which are suitable for the 45 different blocking out steps, for instance the permanent filler indicated at 5 in Fig. 2 may consist of cellulose lacquer, shellac, varnish, etc. The temporary blocking out material indicated at 6 may be glue, mucilage or the like. It is preferable to employ masking 50 materials of different compositions, for instance the blocking out or masking material here referred to as permanent is only soluble with oils, spirits or the like, while the material referred to as temporary blocking out 55 material happens to be water soluble.

With the master stencil prepared as shown in Fig. 3, it is ready for the production of the first masking film indicated at 7 in Fig. 60 4. The material employed for this purpose may be the same as the permanent filler indicated at 5, i. e., it may consist of cellulose lacquer, shellac, varnish or the like. A transfer sheet constructed of paper or the 65 like and having a soluble surface coating

formed thereon is placed below the master stencil. A quantity of film forming material, such as shellac or varnish, is then placed on top of the stencil, and it is forced through the open portion of the stencil indicated at C by means of a squeegee or the like. The film-forming material is thus forced through the open portion of the stencil and as such is deposited on the transfer sheet shown in Fig. 4. The printing 75 stencil indicated in Fig. 5 is often purposely made large to have two or more designs applied thereto; in this case it will only be necessary to make two masking films, one for the design indicated at 8 and one for 80 the design indicated at 9. In actual practice several masking films are often made for attaching to large stencils so that a number of prints can be run simultaneously. However, it is often desirable to file away 85 duplicates for future orders as will herein-after be described. The moment the masking film has been applied to two of the transfer sheets as shown in Fig. 4, and while they are still wet, it is possible to transfer or 90 apply them to the printing stencil shown in Fig. 5, but before describing this transfer or application, a brief description of the printing stencil will be submitted. This stencil, as previously stated, is shown in 95 Figs. 5, 9 and 11. Referring to Fig. 11, it will be noted that the printing stencil consists of a base section D to which is hingedly secured at one end, as at 10, a rectangular-shaped frame 11. A silk bolting cloth or 100 like material is stretched over the frame as indicated at 12 and to this extent it is a duplicate of the master stencil, the only difference being that it is substantially twice as large or larger to accommodate a series 105 of the same design if desired. In order to insure precision or correct placing of the masking films on the lower surface of the printing stencil, a transfer plate E is employed. This is placed on the base member 110 D, as shown in Fig. 11 and it is placed and held in a predetermined position by three or more registers or guides attached to the base as indicated at 14, 15 and 16. Markers are formed on the plate similar to 115 those indicated at 17 (see Fig. 1). The original design shown in Fig. 1 is placed on the plate E in register with the markers and the outline of the design is then traced 120 on the printing stencil as indicated by the circles 18 (see Fig. 11). The area of the stencil exterior of the circles is then filled with a permanent filler such as indicated at 5^a, and when the stencil is so prepared it is 125 ready for the application of the masking films, shown in Fig. 4. This is accomplished as follows:

When the masking film has been transferred from the master stencil to the two or more transfer sheets, as shown in Fig. 4, 130

these sheets are placed on the plate E in register with the markers 17. The printing stencil is then lowered from the position shown in Fig. 11 so that contact is made 5 between the surface of the bolting cloth and the films 7 applied to the transfer sheets, and as these are still wet or adhesive they will adhere to the lower surface of the printing stencil. A light pressure is then 10 applied to the upper surface of the stencil and the film 7 will thus be forced against the fabric and will tightly adhere thereto. The transfer sheets may then be removed, 15 for instance by moistening them and the masking films 7 are thus left on the printing stencil and will assume the position shown in Fig. 5. Before proceeding further, it might be stated that the transfer sheets preferably consist of thin transparent or 20 semi-transparent paper such as tissue-paper or the like, to the upper surface of which is applied a thin coating of mucilage or other soluble matter that will release the film when moistened. These transfer sheets receive 25 the masking film from the master stencil as shown in Fig. 4 and they are transferred to the printing stencil as shown in Fig. 11 by pressing the printing stencil against the films while they are in a wet or adhesive 30 condition, and the transfer sheets may then be readily removed by merely moistening them, as this will loosen the adhesive surface on the transfer sheets and thus release the films, or in other words, permit them to 35 remain on the printing stencil.

With the first masking films applied to the printing stencil as shown in Fig. 5, the printing stencil is ready for the first color run, to-wit, the color red, and as the surface 40 of the printing stencil is closed exterior of the large circle A and interior of the small circle C, it is obvious that the red color to be run will only pass through the open portion of the printing stencil which lies between the two circles, this being shown at 45 8 and 9 in Fig. 5. The card or other material to which the color is to be applied is shown in Fig. 6. It is placed on the base plate D between the aligning pins 14, 15 and 16. The stencil is lowered down into 50 contact therewith, the color is placed on top of the stencil, and it is then forced through the stencil and on to the card 20 (see Figs. 5 and 6) by passing a squeegee 55 over the stencil. Two red circles such as shown at 21 will thus appear on the card 20 (see Fig. 6), and the first operation is completed after as many cards as desired have been made. While the first color is 60 being run through the printing stencil shown in Fig. 5, the art department can be busy preparing the second masking film which is to be applied to the printing stencil. This is accomplished as follows: 65 After the first set of films shown in Fig. 4

have been made and as many duplicates as desired, the master stencil is cleaned off to remove the film-forming material, and it is then washed in water, as the temporary blocking out material indicated at 5, such 70 as glue, mucilage or the like is soluble therein. When the temporary masking material has been completely removed and the master stencil dried, a second coating of temporary masking material is applied, as 75 shown in Fig. 7, i. e., the entire area within the square B is covered with the temporary masking material, as indicated at 22, and when this is set and dry, the master stencil is ready for the production of the second 80 set of masking films. This is accomplished by placing a transfer sheet below the stencil, then placing the film-forming material on top of the stencil and forcing it through the open portion thereof by means of a 85 squeegee or the like. The film-forming material is thus deposited on the transfer sheet as shown at 7^a in Fig. 8, and when so deposited is ready for transfer to the printing stencil. This is accomplished in the 90 same manner, as previously described, i. e., the plate E is placed on the base D and the transfer sheets having the masks 7^a formed thereon are placed in register on top of the plate E, the printing stencil is lowered into 95 forcible engagement therewith and pressure is applied to the upper surface of the stencil so that the film will be pressed into the lower surface of the stencil fabric and securely adhere thereto. The transfer sheets 100 are then moistened so as to partially dissolve the adhesive surface formed thereon and the transfer sheets may thus be peeled off, thereby leaving the masking films on the surface of the printing stencil. The printing stencil so prepared is shown in Fig. 9 and when the film has thoroughly dried 105 and set, the stencil is ready for use. The only surface open on the printing stencil at this time is that portion within the square 110 B and surrounding the inner circle C, the inner circle C having been previously closed by the first masking operation, and the surface exterior of the square and within the large circle A having been closed by the 115 application of the last mask. The cards which were previously printed with the first color run, to-wit, red and shown in Fig. 6, have been dried and as such are replaced one by one between the positioning register 120 guides on the base. The printing stencil is lowered and the color blue is applied on the upper surface and is forced through the open fabric by means of the squeegee. The cards are removed one by one as the color 125 blue is applied and they are then completed as shown in Fig. 10, the design when completed consisting of an inner white circle, a surrounding blue square, and an exterior circle of red. The cards may be cut in two 130

along the dotted lines indicated at 25 and when dry are ready for delivery.

To fully appreciate the advantages of the present method when comparison is made with the old methods disclosed in the patents previously referred to, it should be remembered that the art work, to-wit, tracing, blocking out, etc. is done directly on the printing stencils where the old methods are employed. This is a disadvantage as it ties up the printing stencils while the blocking out work, etc. is being done in the art department and while the blocking out material is drying. By the present method the art work, such as tracing, blocking out, drying, making of masking films, etc. is done in the art department on the master stencil only and while the printing stencil is in use, hence the printing stencils will not be tied up at any time except when the masking films are applied. This requires only a few minutes between each color run.

By the old methods, if a customer orders for instance 1000 posters or designs and there is a chance of a repeat order at some future time, it is necessary to store away the printing stencils. A great quantity of stencils gradually accumulate in this manner, thereby increasing cost and quantity of equipment. The present method reduces the amount of equipment or stencils required as the stencils may be cleaned off for re-use the moment an order is completed due to the fact that transfer sheets with films thereon may be kept in stock for duplication of future orders.

The old methods required duplication of hand or art work where more than one design was grouped on a stencil or on several stencils. This increases the time required; it adds to the cost; and it does not lend itself to accuracy or precision work. The present method insures absolute accuracy as the only art work required is done on the master stencil. This in turn produces the masking films and as these may be applied to one or more stencils, it is obvious that it eliminates duplication of hand or art work where more than one design is grouped on a single stencil, or several stencils, and it also insures accuracy and uniformity throughout.

While a more or less primitive type of printing stencil is illustrated in the present application, it is obvious that the present method is not limited thereto, as it is equally applicable where stencil printing machines are employed (see the patent to Edward A. Owens entitled "Stencil printing machine," No. 1,490,400, issued April 15, 1924).

While certain features of the present invention are more or less specifically described, I wish it understood that various changes may be resorted to within the scope

of the appended claims. Similarly, that the materials and finishes of the several parts employed may be such as the manufacturer may decide or varying conditions or uses may demand.

Having thus described my invention, what I claim and desire to secure by Letters Patent is:

1. A method of preparing masking films and applying them to printing stencils which consists in copying the pattern of the mask on the surface of a permeable master stencil, blocking out the surface exterior of the pattern so as to leave the surface interior of the pattern permeable, placing a transfer sheet below the master stencil, forcing a film-forming material through the permeable surface of the master stencil so as to deposit the material in the form of a film on the transfer sheet and then transferring the film from the transfer sheet to the printing stencil.

2. A method of preparing masking films and applying them to printing stencils which consists in tracing the outline of the mask on the surface of a permeable master stencil, blocking out the surface exterior of the outline so as to leave the surface interior of the outline permeable, placing a transfer sheet below the master stencil, said sheet being coated with a soluble material, forcing a film-forming material through the permeable surface of the master stencil so as to deposit the material in the form of a film on the coated surface of the transfer sheet, placing the transfer sheet with a masking film thereon below the printing stencil, applying the masking film to the surface of the printing stencil, and then dissolving the coating on the transfer sheet to remove the transfer sheet.

3. In a method of preparing masking films for printing stencils, the steps which consist in depositing the film on a paper coated with soluble material, applying the film when so transferred to the surface of a printing stencil and then dissolving the coating on the paper to remove the paper.

4. A method of preparing masking films and applying them to printing stencils, which consists in forcing a film forming material, through a stencil, and depositing the film forming material in the form of a film on a transfer sheet, which is coated with a soluble material, placing the transfer sheet with the masking film thereon against the surface of a printing stencil, applying the masking film to the surface of the printing stencil, and then dissolving the coating on the transfer sheet to remove the transfer sheet.

EDWARD A. OWENS.
